REFRIGERATOR DOOR

Roland H. Money, Cincinnati, Ohio, assignor to
The Crosley Corporation, Cincinnati, Ohio, a
corporation of Ohio

Application August 18, 1938, Serial No. 225,600

7 Claims. (Cl. 20—35)

My invention relates to refrigerator doors and particularly to the structural features thereof.

In the art it has been customary to manufacture refrigerator doors from front and back panels, the front panel being formed in a box-like arrangement with a rear wall opening for receiving insulation. The back panels have been secured to wooden strips, which strips have extended within the rear wall openings of the front panel. The front panels have been formed with the rear walls having edge portions inclined so as to contact the wooden strips and be secured thereto. Then breaker strips have provided an interlock between the front and back panels and the wooden strips, the breaker strips being screwed or bolted to the wooden strips in closely spaced positions so as to make the whole assembly rigid.

It is the object of my invention to provide a greatly simplified door construction wherein the front and back panels are rigidly secured together with brackets which obviate the necessity of a multiplicity of screws and a braced support depending substantially on the interlock of the breaker strip between the front and rear panels.

Another object is the provision of a refrigerator door which, though constructively much stronger, may be erected at a considerably lower cost of assembly.

The above objects and other objects to which reference will be made in the ensuing disclosure, I accomplish by that certain combination and arrangement of parts of which I have shown a preferred embodiment.

Referring to the drawings:

Figure 1 is a perspective view from the inner side of the metallic outer front panel.

Fig. 2 is a lateral sectional view taken along the line 2—2 of Fig. 1.

Fig. 3 is a vertical sectional view showing the metallic outer front panel after the pads of insulating material have been inserted.

Fig. 4 is an elevation from the rear of the panel shown in sectional view in Fig. 3, the bracing strips being illustrated in position ready to be inserted.

Fig. 5 is a perspective view from the rear side of the door showing the door assembly with the inner panel in position and with a portion of the door sealing strip also shown.

Fig. 6 is a sectional view along the lines 6—6 in Fig. 5.

Fig. 7 is a perspective view from the rear of the door showing the manner of mounting the breaker strips.

Fig. 8 is a perspective view from the rear of the door after the breaker strips have been secured in position.

Fig. 9 is a sectional view taken along the lines 9—9 in Fig. 8.

Fig. 10 is a side elevation of a corner supporting member which interlocks the edges of the breaker strip at the four corners of the door.

Fig. 11 is a rear elevation of the corner molding piece illustrated in side elevation in Fig. 10.

Fig. 12 is a sectional view taken along the lines 12—12 in Fig. 11.

The refrigerator door is composed of a front panel 1, contoured across the front face of the door as indicated at 2. The panel extends backwardly and forms side edge portions 3, and then the metal is formed with inwardly extending portions 4, which outline an opening 5 in the rear of the main door panel.

It is this opening or box-like compartment 20 which receives the insulation padding material 6, which is ordinarily formed of sheets of fibrous insulative material.

Angle strips or bands 7 extend across the corners of the inwardly extending portions which outline the insulation opening in the door and to the strips 1, are secured spacing brackets 8.

After the insulation is in position, strips which may conveniently be formed of wood 9, are secured in position with the inner edges of the strips bearing against it.

The internally flanged portions which form the rear opening in the door for receiving insulation, have edge portions 10, which form ledges which receive the inner edges of the wooden strips 9, so as to hold these strips in position. The inner door panel 11 is provided with channeled portions 12 which receive the outer edges of the strips 9, and so hold these strips 9 in position. Machine screws 13 extend through the inner door panels 40 and are received in internally threaded nuts 14, welded to the spacing brackets 8.

Thus it will appear that the wooden strips form spacing members which extend between the outer and inner door panels, being held in position securely by being clamped between the outer and inner door panels. When the screws 13 are tightened down the strips 9 are held rigidly in position. Further the only metal to metal contact is through the spacing brackets 8.

Hinges 15 are secured to the side portions 3 of the front panel. Only a portion of the hinge mechanism is illustrated and it forms no part of my invention.

Fig. 5 shows the assembly of the door includ-

- ing the step of inserting the rubber sealing strip 16, which is of rectangular outline and fits against the internally flanged portions 4 of the front panel, being secured as indicated in Fig. 6 5 by means of tacks 17, to the wooden strips 9. It will further be observed that the resilient sealing strips have flanged edge portions 18 forming a channel 19 which receives the inner edges of the breaker strips.
- 10 In Fig. 7 the breaker strips 20 are shown as they are assembled. The inner edges are received in the channels 19 and wood screws 21 extend through holes 22 in the breaker strips and thus secure the breaker strips in position, firmly 15 cured to the wooden strips 9.
- Fig. 9 best illustrates the complete assembly of the door. The general appearance of the door after it is completely assembled is best illustrated in Fig. 8.
- 20 Prior to completion of the assembly, corner pieces generally indicated at 23, are inserted at the four corners of the door. The molded corner pieces are formed with channels 24, which receive the end edges of the breaker strips.
- 25 The door, assembly of which has just been described, is economical to manufacture and the assembly in factory production can be conveniently made by a series of operations as the door moves along, one operator performing one step 30 and the next operator performing another. There is not only provided a door, the assembly of which can be carried out with a minimum of labor, but after the door is completely assembled, it will be found to be insulatively very efficient 35 and the appearance is pleasing. The door is not only constructively strong and durable and efficient as far as its insulative properties are concerned, but there is less cost for material and construction than in any other type of refrigerator door with which I am familiar.
- Having thus described my invention, what I claim as new and desire to secure by Letters Patent is:
1. A refrigerator door having a metallic outer 45 front panel contoured across the front face of the door, then extending backwardly forming side edges of the door and then extending inwardly, forming flanged portions outlining an opening formed in the door for receiving fibrous insulation, said flanged portions terminating in lips extending backwardly and inwardly and bracing strips secured diagonally across the corners of the flanged portions in back of the door opening and having bracket portions 50 extending to positions spaced inwardly from said flanged portions and provided with means for securing an inner door panel in position on the door.
2. A refrigerator door having a metallic outer 55 front panel contoured across the front face of the door, then extending backwardly forming side edges of the door and then extending inwardly, forming flanged portions outlining an opening formed in the door for receiving fibrous insulation, said flanged portions terminating in lips extending backwardly and inwardly and bracing strips secured diagonally across the corners of the flanged portions in back of the door opening and having bracket portions 60 extending to positions spaced inwardly from said flanged portions and provided with means for securing an inner door panel in position on the door, said inner door panel having peripheral flanged portions and wooden strips secured in position in said door between the front and back panels, the front edges of the strips bearing against the bracing strips, the inside surfaces of the strips bearing against the said bracket portions and the back edges of the strips bearing against the peripheral flanged portions of the inner panel.
3. A refrigerator door having a metallic outer 65 front panel contoured across the front face of the door, then extending backwardly forming side edges of the door and then extending inwardly, forming flanged portions outlining an opening formed in the door for receiving fibrous insulation, said flanged portions terminating in lips extending backwardly and inwardly and bracing strips secured diagonally across the corners of the flanged portions in back of the door opening and having bracket portions 70 extending to positions spaced inwardly from said flanged portions and provided with means for securing an inner door panel in position on the door, said inner door panel having peripheral flanged portions and wooden strips secured in position in said door between the front and back panels, the front edges of the strips bearing against the bracing strips, the inside surfaces of the strips bearing against the said bracket portions and the back edges of the strips bearing against the peripheral flanged portions of the inner panel.
4. A refrigerator door having a metallic outer 75 front panel contoured across the front face of the door, then extending backwardly forming side edges of the door and then extending inwardly, forming flanged portions outlining an opening formed in the door for receiving fibrous insulation, said flanged portions terminating in lips extending backwardly and inwardly and bracing strips secured diagonally across the corners of the flanged portions in back of the door opening and having bracket portions extending to positions spaced inwardly from said flanged portions and provided with means for securing an inner door panel in position on the door, said inner door panel having peripheral flanged portions and wooden strips secured in position in said door between the front and back panels, the front edges of the strips bearing against the bracing strips, the inside surfaces of the strips bearing against the said bracket portions and the back edges of the strips bearing against the peripheral flanged portions of the inner panel, and breaker strips secured to said wooden strips.
5. A refrigerator door having a metallic outer 80 front panel contoured across the front face of the door, then extending backwardly forming side edges of the door and then extending inwardly, forming flanged portions outlining an opening formed in the door for receiving fibrous insulation, said flanged portions terminating in lips extending backwardly and inwardly and bracing strips secured diagonally across the corners of the flanged portions in back of the door opening and having bracket portions extending to positions spaced inwardly from said flanged portions and provided with means for securing an inner door panel in position on the door, said inner door panel having peripheral flanged portions and wooden strips secured in position in said door between the front and back panels, the front edges of the strips bearing against the bracing strips, the inside surfaces of the strips bearing against the said bracket portions and the back edges of the strips bearing against the peripheral flanged portions of the inner panel, and breaker strips secured to said wooden strips.
6. A refrigerator door comprising front and back panels, the front panel formed into a box-like assembly having spaced front and rear walls and a rectangular opening in the rear wall for the reception of insulating material, and means secured to said rear wall back of said rectangular opening for supporting said back panel in spaced position from said rear wall, wooden strips extending between the back panel and the rear wall of the front panel, said strips having a side edge bearing against said aforenoted means.
7. A refrigerator door comprising front and back panels, the front panel formed into a box-like assembly having spaced front and rear walls and a rectangular opening in the rear wall for the reception of insulating material, and means secured to said rear wall back of said rectangular opening for supporting said back panel in spaced position from said rear wall, wooden strips ex- 85

tending between the back panel and the rear wall of the front panel, said strips having a side edge bearing against said aforesaid means, and breaker strips supported at the side edges thereof between said back panel and the rear wall of said front panel.

7. A refrigerator door comprising front and back panels, the front panel formed into a box-like assembly having spaced front and rear walls and a rectangular opening in the rear wall for the reception of insulating material, and means

secured to said rear wall back of said rectangular opening for supporting said back panel in spaced position from said rear wall, wooden strips extending between the back panel and the rear wall of the front panel, said strips having a side edge bearing against said aforesaid means, and breaker strips supported at the side edges thereof between said back panel and the rear wall of said front panel, said breaker strips secured to said wooden strips. 5
